UNITED STATES PATENT OFFICE.

HERMAN C. SCHMIDT, OF JOHNSTOWN, NEW YORK.

EXTENSION FIRE-LADDER AND TRUCK.

SPECIFICATION forming part of Letters Patent No. 437,625, dated September 30, 1890.

Application filed November 20, 1889. Serial No. 330,996. (No model.)

To all whom it may concern:

Be it known that I, HERMAN C. SCHMIDT, a citizen of the United States, and a resident of Johnstown, in the county of Fulton and State of New York, have invented certain new and useful Improvements in Extension Fire-Ladders and Trucks; and I do hereby declare that the following is a full, clear, and exact description of the invention, which will enable others skilled in the art to which it appertains to make and use the same.

My invention relates to improvements in extension fire-ladders and trucks; and it consists in the novel features of construction and new combination of parts hereinafter more fully described, and definitely pointed out in the claims.

In the accompanying drawings, Figure 1 is a side elevation of the forward part of a truck and extension-ladders constructed in accordance with my invention, the ladders being shown lowered in full lines and raised in dotted lines. Fig. 2 is a plan view of the same. Fig. 3 is a detail view of the mechanism by which the lower ladder-sections are raised and lowered. Fig. 4 is a side elevation of the rear portion of the truck. Fig. 5 is a plan view of the same. Fig. 6 is a cross-section on the line $\alpha\alpha$, Fig. 5, looking toward the front. Figs. 7 and 8 are detail views showing the manner of securing the rounds to the lower or truss ladder. Figs. 9 and 10 are side and end views, respectively, of the means for securing the sections of the lower ladder vertically and laterally, the rods securing the sides laterally also serving as guides for the upper ladder. Fig. 11 is a sectional view of the rings which support and carry the ladders. Fig. 12 is a detail perspective view of the tillerman's seat.

In the said drawings, the reference-numerals 1 and 2 denote the axles, and 3 the supporting-wheels. To these axles are secured the springs 4 4, which support the lower sections 5 5 of a turn-table, being secured rigidly thereto.

6 6 designate the upper sections of the turn-tables, which are secured to the supporting-rails 7 7 by means of the arms or braces 8 8, which are firmly secured thereto and to the sections 6 6. These rails 7 7 are parallel to each other, connecting the front

and rear turn-tables and wheels and axles together and form the main frame of the truck. The upper and lower sections of the turn-tables consist of circular plates or rims pivoted together at their centers, so that the lower section, carrying the axles and wheels, may readily turn on said pivots, so as to guide the truck and enable it to make short turns. 55 60

To the forward ends of the rails 7 7 an annular or flat ring 9 is secured by means of screw-bolts 10. Mounted upon this annulus 9 is another annulus 11, which is capable of freely revolving thereupon. This annulus 11 65 consists of an upper ring 12, a depending wall 13, and a lower ring 14, of less diameter than ring 12, thus forming a peripheral groove 15, within which the annulus 9 is received, thus enabling the upper annulus 11 70 to freely revolve upon the annulus 9 without any danger of being displaced by the weight of the ladders.

16 16 designate four upwardly-projecting lugs, secured to the annulus 11 and carrying 75 the screw-threaded bars 17 17, which can freely revolve therein. The forward ends of these bars are provided with pinions 18 18, meshing with corresponding pinions 19 19 on the shaft 20, so that rotary motion imparted to 80 said shaft by a crank or otherwise will be communicated to said screw-bars 16 16. The shaft 20 has its bearings in the arms 21, secured to the triangular frames 22 22, which are secured at their bases to the annulus 11 85 and united at their apices by the cross-bar 23. Pivoted to the cross-bar are the short arms 24 24, which are also pivoted to the apices of the triangular frames 25 25. It should be here stated that the distance between the triangular frames 22 22 is a little greater than the width of the ladder, the lower ends of which are embraced between them. The rear ends of frames 25 25 are connected together by means of a cross-bar 95 26 below the lower section 27 of the truss-ladder 28, and pivoted to these ends are the arms 29 29, which extend upwardly and are secured to the pivotal cross-bar 30, having its bearings in the journals 31, secured to the upper section 32 of the truss or lower ladder. 90

The front ends of the frames 25 25 are provided with screw-threaded lugs 25^a 25^a, pivotally secured thereto, through which the

screw-bars 17 pass. The lower ends of the truss or lower ladder are pivoted in the cross-bar 33, pivoted in the sides of frame 22. The upper and lower sections 32 and 27 of the 5 truss-ladder are united by the double T-plates, which consist of a vertical portion 34 and horizontal webs 35, the latter being provided with apertures for the passage of the screw-bolts, which also pass through the side 10 rails of the ladders and are secured by the binding-nuts 37. These plates are connected laterally by means of the upper and lower cross-bars 38 38, secured to said plates. The rounds 39 of the ladder are secured to the 15 upper truss-section by means of sockets 40, consisting of a plate 41, having holes for the passage of screws or other fastening devices, and a central recessed boss 42, in which the ends of the round are inserted.

20 The cross-bar 33 can be revolved in the frames 22, and for this purpose is provided at either or both ends with pinions 43, engaging with pinions 44 on the shafts 45, which are turned or rotated by cranks 46 or otherwise.

25 Mounted centrally upon the pivot-bar 33 is a sprocket-wheel 47, over which passes a sprocket - chain 48. The sprocket - chain passes upward or backward to near the rear end of the truss-ladder and passes over an 30 other sprocket-wheel 49, rigidly mounted upon a pivot-bar 50, pivoted in the side rails or lower sections of the truss-ladder. The ends of the sprocket-chain are connected together by means of a link or bar 51, secured to the 35 lower rounds of the upper ladder 52. This ladder 52 is of ordinary construction, consisting of side rails connected together by the usual round. The extreme rear ends of the upper and lower sections of the truss-ladder 40 are secured together by means of clamping-bars 53 and bolts and nuts 54 and 55, and to these bars are secured or formed therewith the lugs 56 56, having apertures, through which pass the screw-threaded rods 57 57. These 45 rods 57 are provided with hand-nuts 58 58, having screw-threaded apertures, by means of which they are adjustable vertically upon the said bars, whereby their height above the ladder may be regulated. At their upper 50 ends the bars 57 are provided with sheave wheels or rollers 59 59, over which the tension chains or ropes 60 60 pass. These tension chains or ropes at their lever ends are secured to the lower ends of the upper ladder 55 and pass upwardly under the rollers 61 61, mounted on cross - bar 61^a, pivoted in the truss-ladder over the sheaves 59 to the upper or rear ends of the upper ladder, where they are secured.

60 My improved brake mechanism is constructed as follows: Secured to the rear of the lower section 5 of the front turn-table of the front axle are the arms 62 62, in which is pivoted a transverse bar 63, having its ends bent downwardly, forming short arms 64 64, which carry the brake-shoes 65 65. Rigidly secured at the center of bar 63 is the bent lever 66,

which extends downwardly a short distance and then forwardly, where it is secured to the vertical cranked rod 67. The upper end of the rod 67 is secured to the horizontal lever 68, which is fulcrumed at or near its center to the upper annulus 11, so as to be movable vertically upon its fulcrum, and its forward end is bent upwardly into a foot-lever 69.

70 Secured to the rear of the main or side rails of the truck is the frame for supporting the tillerman's sliding seat. This frame consists of the double bifurcated side arms 70, secured at their lower bifurcated ends to the 80 main rails 77 by means of bolts and nuts, and are connected together laterally by the transverse bar 72. The upper bifurcated ends of the supporting-arms 70 71 are provided with holes or apertures for the passage of the rods 85 74 74, which are united near their inner ends by the rod 75, pivoted therein, said rod 75 being extended over horizontally beyond the rods 74. The rod 75 is swung over the end of the opposite supporting-arms 71, so as to engage therewith and hold the seat-frame securely in place. The seat-frame is composed of the two parallel cross-bars 76, having their ends bent downward and secured to the ends of rods 74 74, said bars 76 being united centrally by the connecting-bar 77, which carries the seat 78 at its rear end. At its forward end this bar is provided with a socket 79, through which the tiller-shaft 80 passes, the lower end of which engages with a socketed 90 shaft 81, secured to the upper section of the turn-table, and carrying at its lower end a pinion engaging with a segment secured to the lower section of the turn-table, and by means of which the axle and wheels may be 95 turned through the medium of the tiller-wheel 84.

100 The numerals 85 85 designate central and rear end cross-bars, uniting rails 77 and projecting above the top thereof, so as to support 110 and form rests for the ladders.

The operation of the apparatus is as follows: In its normal position the truss-ladder is lowered, resting upon the central bar 85 of the side rails 7, the upper ladder also being 115 lowered and embraced within the truss-ladder. The seat-frame is extended inward and above the ladders, with the cross-bar 75 turned over the ends of the opposite side arms 71 and the free ends of the rods 74 resting in the apertures therein. When it is desired to raise the ladders, the tiller is first unshipped and the bar 75 released from engagement with side arms 71 by turning it upward upon its pivots and the seat-frame slid back out of the way, 120 the rods 74 sliding in the apertures in the side arms 70, thus allowing a free passage-way for the movement of the ladders. Shaft 20 is now revolved by means of cranks or other suitable instruments, causing a rotary motion 130 to be imparted to the screw rods or bars 17 through the medium 18 and 19. This rotary motion of rods 17 causes the lugs 25^a, secured to lever or front end of frames 25, to be moved

rearwardly, elevating the rear ends of said frames, and through its pivotal connections 29 and 24 elevating the truss-ladder, which turns upon the pivot-bar 33.

5 When the truss-ladder has been elevated to its proper position, the upper ladder is extended as follows: Sprocket-wheel 47 on bar 33 is revolved by means of cranks 46 on shafts 45 through the medium of pinions 43 and 44. 10 This rotation of sprocket-wheel 47 causes link 51 of sprocket-chain 48 to be moved upwardly, carrying with it the upper ladder 52, which is guided in its upward movement by the guides formed by the cross-bars of double T-15 plate, which connect the upper and lower sections of the truss-ladder.

The tension chains or ropes 60 serve to give rigidity to the upper ladder and prevent any bulging or bending thereof.

20 The ladders may be provided with guy ropes or chains to prevent lateral swaying.

A reversal of the operations above described will lower the ladders and cause them to assume their normal positions.

25 The brakes are operated as follows: When it is desired to apply the same, the foot-lever 69 is depressed, which elevates the rear end of lever 68, elevating the cranked rod 67, which in turn elevates the front end of bent lever 66, which, being rigidly connected with transverse bar 63, causes the latter to turn slightly in its pivotal bearings, and thus bring the brake-shoes in contact with the wheels.

The apparatus is simple in its construction, 35 and will be found very efficient in operation, as the ladders can be elevated or extended with ease in a very short time and be lowered with equal facility.

The annular ring by which the ladders are 40 supported and carried is movable or revolvable upon the lower ring, so that the ladders can be readily turned to any point of the compass desired, thus enabling different buildings or different parts of a building to be 45 reached without disturbing the truck.

The parts of the apparatus by which the ladders are operated, being located low down or near the ground, will enable the persons operating the same to do so without mounting 50 the apparatus.

The invention possesses other advantages not herein enumerated, but which will be manifest to those who have a knowledge of the requirements of this class of apparatus, 55 and therefore do not need to be set forth.

Having thus described my invention, I claim and desire to secure by Letters Patent of the United States—

1. The combination, with the rings or annuli 9 and 11, the latter being revolvable upon the former and having the lugs 16 16, and the frames 22 22, of the screw rods or bars 17 17, working in said lugs, the truss-ladder pivoted in frames 22 22, and frames 25 25, secured to said ladders and pivoted in frames 22 22 and engaging with screw rods or bars 17 17, substantially as described.

2. The combination, with the rings or annuli 9 and 11, the latter being revolvable upon the former and provided with lugs 16 16, the screw rods or bars 17 17, working in said lugs, and the frames 22 22, united by cross-bar 23, of the truss-ladder pivoted in said frames 22 22, the frames 25 25, pivotally connected to the truss-ladder, and the screw-threaded lugs 75 25^a 25^a, pivoted to the front lower end of frames 25 25 and with which the screw-rods 17 17 engage, substantially as described.

3. The combination, with the rings or annuli 9 and 11, the latter being revolvable upon the former and provided with lugs 16 16, the screw rods or bars 17 17, working in said lugs, and the frames 22 22, united by cross-bar 23, of the truss-ladder having depending pivoted arms 29 29, the frame 25 25, pivoted to arms 85 29 29, the arms 24 24, pivoted to frames 25 25 and 22 22, and the lugs 25^a 25^a, secured to frame 25 25 and engaging with screw-rods 17 17, substantially as described.

4. The combination, with the rings or annuli 9 and 11, the latter being revolvable upon the former and provided with lugs 16 16, screw-rods 17 17, having pinions 18 18, and the shaft 20, having pinions 19 19 meshing with pinions 18 18, of the truss-ladder pivoted in frame 22 95 22, the frames 25 25, pivoted connections 29 29 and 24 24, and the lugs 25^a 25^a, engaging with screw-rods 17 17, substantially as described.

5. The combination, with the rings or annuli 9 and 11, the latter being revolvable upon the former and provided with lugs 16 16, the screw bars or rods 17 17, and frames 22, of the truss-ladder, the frame 25 25, the pivoted connections 29 and 24, the lugs 25^a 25^a, the pivot-bar 33, sprocket-wheels 47 and 49, sprocket-chain 48, and the upper ladder 52, connected with the sprocket-chain, substantially as described.

6. The combination, with the rings or annuli 9 and 11, the latter being revolvable upon the former and provided with lugs 16 16, the screw-bars 17 17, having pinions 18 18, the shaft 20, having pinions 19 19, the frames 22 22, having pivot-bar 33, provided with pinions 43 43, and the shafts 45 45, having pinions 44 44, of the truss-ladder pivoted in frame 25 25, the sprocket-wheels 47 and 49, the sprocket-chain 48, and the upper ladder 52, to which the sprocket-chain is secured, substantially as described.

7. The combination, with the truss-ladder and the extension or upper ladder 52 and means, substantially as described, for operating the same, of the lugs 56 56, secured to the rear or upper ends of the truss-ladder, the rods 57 57, having sheaves 59 59, and the tension chains or ropes 60 60, secured to the truss and extension ladders and passing over sheaves 57 57, substantially as specified.

8. The combination, with the truss-ladder and the extension or upper ladder 52 and means, substantially as described, for operating the same, of the lugs 56 56, secured to the

truss-ladder, the screw-threaded rods 57 57, having sheaves 59 59, the hand-nuts 58 58, and the tension chains or ropes 60 60, secured to the truss and extension ladders, substantially 5 as described.

9. The combination, with the truss-ladder and the upper or extension ladder 52 and means, substantially as described, for operating the same, of the lugs 56 56, secured to the 10 truss-ladder and having central apertures, the screw-threaded rods 57 57, having sheaves 59 59, the screw-threaded hand-nuts 58 58, engaging in the rods 57 57, the cross-bar 61*, pivoted in the truss-ladder and carrying the 15 rollers 61 61, and the tension chains or ropes 60 60, substantially as specified.

10. The combination, with the upper and lower sections 32 and 27 of the truss-ladder, of the double T-plates consisting of a vertical 20 portion 34 and horizontal webs 35, secured to said sections, and the cross-bars 38 38, secured to said plates, substantially as described.

11. The combination, with the side rails 7 25 7 of the truck, of the side arms 70, secured at their lower ends to said side rails, and their upper ends carrying a laterally-sliding seat-frame, substantially as described.

12. The combination, with the side rails 7 30 7 of the truck, of the side arms 70 70, secured at their lower ends to the said side rails and having their upper ends perforated or provided with apertures 73, and the transverse rods 74 74, movable or slidable in said aper-

tures and supporting the seat-frame, substantially as described. 35

13. The combination, with the side rails 7 7 of the truck, of the side arms 70, secured at their lower ends to the side rails and having their upper or free ends provided with apertures 73 73, the transverse rods 74 74, movable or slidable in said apertures, and the cross-bars 76 76, forming the seat-frame, connected with rods 74 74, substantially as described. 40

14. The combination, with the side rails 7 45 7 of the truck, of the side arms 70 70, secured at their lower ends to the side rails and having their upper or free ends provided with apertures 73 73, the transverse rods 74 74, movable or slidable in said apertures, the 50 cross-bars 76 76, forming the seat-frame, connected with said rods 74 74, and the horizontal pivoted rod 75, adapted to secure and hold the seat-frame in place, substantially as described.

15. The combination, with the side rails 7 7 of the truck, of the side arms 70 70, having apertures 73 73, the transverse rods 74 74, the cross-bar 76 76, the pivoted rod 75, the connecting-bar 77, the seat 78, the socket 79, and 60 tiller-shaft 80, substantially as described.

In testimony that I claim the foregoing as my own I have hereunto affixed my signature in presence of two witnesses.

HERMAN C. SCHIMIDT.
